UNITED STATES PATENT OFFICE.

CHRIS NOHR, OF PASADENA, AND PETER NOHR, OF LOS ANGELES, CALIFORNIA.

MACHINE FOR ROLLING SOLES.

Application filed December 22, 1927. Serial No. 241,812.

This invention relates to shoe making machinery.

One method of applying soles to the uppers of shoes is by cementing, and in order to efficiently carry out this method of manufacture it is necessary to press the sole very firmly into place so that the cement interposed between the sole and the upper will be of equal thickness to provide a strong bond. It is an object of this invention, therefore, to provide a machine for efficiently rolling and pressing the sole, this machine being an improvement of that disclosed in our co-pending application, Serial No. 228,238, filed October 24, 1927.

Another object of the invention is to provide a machine having a roller adapted to firmly press a shoe sole upon the shoe upper, said roller being concave so as to conform to the transverse curvature with which shoe lasts are ordinarily provided, with the result that even pressure may be applied to the shoe sole throughout its entire area.

The invention possesses other objects and features of advantage, some of which, with the foregoing, will be set forth in the following description of the preferred form of our invention which is illustrated in the drawings accompanying and forming part of the specification. It is to be understood that we do not limit ourselves to the showing made by the said drawings and description, as we may adopt variations of the preferred form within the scope of our invention as set forth in the claims.

Referring to the drawings wherein similar reference characters designate similar parts throughout:

Figure 1 is a side elevation of the press of our invention.

Figure 2 is a front elevation of the press of Figure 1.

Figure 3 is a top plan view of the press, parts being broken away to better reveal the structure.

The press of our invention comprises a base 1 having laterally extending feet 2, preferably at each end, with apertures 3 therethrough permitting rigid mounting of the device upon a suitable support. A pair of upwardly extending spaced lugs 6 and a pin 7 extending therethrough provide a pivotal mounting for a support 8 upon the upper end of which a last 9 is carried. Preferably the manner of mounting the last 9 upon the support 8 is such that the last 9 is interchangeable,

able, permitting the accommodation of shoes of various sizes. The pivot pin 7 is arranged in parallelism with the major axis of the base 1 so that a certain degree of pivotal movement of the support 8 and the last 9 transversely of the base 1 is permitted.

A pair of lugs 11 extend laterally from the base 1 forward of the lugs 6 and have threaded therein at opposite ends pins 12 which provide a pivotal mounting for a frame 13 which is preferably U shaped so that the upper portion 14 which joins the two legs 16 and 17 provides a convenient grip 18 for reciprocation of the frame 13 longitudinally of the base 1 about its pivotal mountings 12. A roller cage 21 is slidable longitudinally of the frame 13 and has revolubly mounted therein a roller 22. The proportionate size and arrangement of the parts are such that the roller 22 normally rests upon the upper surface of the last 9. A lever 23 is pivoted as at 24 to the leg 17 of the frame 13 and a pawl 26 carried by the free end of the lever 23 is adapted to engage a ratchet 27 upon the leg 16 of the frame 13 to adjustably limit the upper movement of the lever 23. A spring 28 under compression between the lever 23 and the roller cage 21 urges the roller 22 downwards upon the last 9, it being understood that in order to increase the pressure of the roller thereupon the lever 23 may be depressed so as to increase the compression of the spring 28. It is customary in the shoe making art to utilize lasts which are provided with a convex surface and preferably the roller 22 which we employ is concave to conform to the convexity of the last, the purpose being to exert even pressure throughout the entire area of the sole so as to squeeze the cement between the sole and the shoe upper to a constant thickness.

An auxiliary table 31 is carried by the base 1 through the expedient of a standard 32, slidable longitudinally of the base 1 and on which standard the table 31 is mounted for vertical adjustment. When the desired vertical adjustment has been attained the table 31 may be locked upon the standard 32 by a clamping screw 33; and a clamping screw 34 permits locking the standard 32 in an adjusted position upon the base 1.

In the operation of our device a shoe upper is positioned upon the last 9. Cement is then applied to the upper and the sole positioned thereupon, it being understood that access to the last is permitted by swinging the frame

13 until the roller 22 is supported upon the table 31. When the shoe and sole are in readiness the frame 13 is swung upon its pivotal mounting so that the roller 22 presses upon the sole; and then by depressing the lever 23 the spring 28 may be suitably compressed to increase the pressure of the roller. Reciprocation of the frame 13 backwards and forwards will then produce a rolling movement of the roller across the sole with the result that the sole will be efficaciously pressed into position upon the upper.

The concavity of the roller 22 has been found to produce a much more efficient cementing of the sole on the upper because of the fact that a roller having parallel sides has been found to exert a large amount of pressure on the sole at its center but very little at its edges. If it should be desired to exert still more pressure on the edges the pivotal mounting 7 of the last 9 provides convenient means for so positioning the last that one of the lateral edges at a time may have the roller reciprocated there across so that a relatively heavy pressure may be applied to the sole at any selected area.

We claim:

1. A machine for rolling shoe soles, comprising a base, a last pivotally mounted on said base for movement laterally thereof, a frame pivoted to said base for movement longitudinally thereof, a roller cage slidably carried by said frame above said last, a concave roller revolvably mounted in said cage, a lever pivoted to one side of said frame and extending transversely thereof above said cage, a spring interposed between said lever and cage to urge the roller onto the last, a ratchet and pawl engagement between said lever and frame for regulating the pressure of said spring, and an auxiliary table adjustably mounted on said base adjacent to the last to receive the roller to permit access to the last.

2. A machine for rolling shoe soles, comprising a base, a last pivotally mounted on said base for movement laterally thereof, a frame pivoted to said base for movement longitudinally thereof, a roller cage slidably carried by said frame above said last, a concave roller revolvably mounted in said cage, a lever pivoted to one side of said frame and extending transversely thereof above said cage, a spring interposed between said lever and cage to urge the roller onto the last, means for regulating the pressure of said spring, and an auxiliary table adjustably mounted on said base adjacent to the last to receive the roller to permit access to the last.

3. A machine for rolling shoe soles, comprising a base, a last pivotally mounted on said base for movement laterally thereof, a frame pivoted to said base for movement longitudinally thereof, a roller cage slidably carried by said frame above said last, a concave roller revolvably mounted in said cage, a lever pivoted to one side of said frame and extending transversely thereof above said cage, a spring interposed between said lever and cage to urge the roller onto the last, means for regulating the pressure of said spring, and an auxiliary table adjustably mounted on said base adjacent to the last to receive the roller to permit access to the last.

prising a base, a last pivotally mounted on said base for movement laterally thereof, a frame pivoted to said base for movement longitudinally thereof, a roller cage slidably carried by said frame above said last, a concave roller revolvably mounted in said cage, a lever pivoted to one side of said frame and extending transversely thereof above said cage, means associated with said lever for urging said roller onto the last, and an auxiliary table mounted on said base adjacent to the last to receive the roller to permit access to the last.

4. A machine for rolling shoe soles, comprising a base, a last pivotally mounted on said base for movement laterally thereof, a frame pivoted to said base for movement longitudinally thereof, a roller cage slidably carried by said frame above said last, a concave roller revolvably mounted in said cage, means associated with said lever for urging said roller onto the last, and an auxiliary table mounted on said base adjacent to the last to receive the roller to permit access to the last.

5. A machine for rolling shoe soles, comprising a base, a last pivotally mounted on said base for movement laterally thereof, a frame pivoted to said base for movement longitudinally thereof, a roller cage slidably carried by said frame above said last, a concave roller revolvably mounted in said cage, and means associated with said lever for urging said roller onto the last.

6. A machine for rolling shoe soles, comprising a base, a last pivotally mounted on said base for movement laterally thereof, a frame pivoted to said base for movement longitudinally thereof, a roller cage slidably carried by said frame above said last, a roller revolvably mounted in said cage, and means associated with said lever for urging said roller onto the last.

7. A machine for rolling shoe soles, comprising a base, a last mounted on said base, a frame pivoted to said base, a roller cage slidably carried by said frame above said last, and a roller revolvably mounted in said cage, said frame adapted to be reciprocated to move said roller across said last.

8. A machine for rolling shoe soles, comprising a base, a last mounted on said base, a frame pivoted to said base, and a roller carried by said frame, said frame being adapted for reciprocation to cause movement of said roller across said last.

In testimony whereof we have signed our names to this specification.

CHRIS NOHR.
